UNITED STATES PATENT OFFICE.

THEODORE FANTA, OF CHICAGO, ILLINOIS, ASSIGNOR TO EARNSHAW KNITTING COMPANY, OF CHICAGO, ILLINOIS, A CORPORATION OF ILLINOIS.

UNDERSHIRT.

1,000,390.

Specification of Letters Patent. Patented Aug. 15, 1911.

Application filed February 3, 1911. Serial No. 606,310.

To all whom it may concern:

Be it known that I, THEODORE FANTA, a citizen of the United States, residing at Chicago, in the county of Cook and State 5 of Illinois, have invented certain new and useful Improvements in Undershirts, of which the following is a specification.

This invention relates to undershirts particularly adapted and intended for infants' 10 wear and aims to provide a garment of this character which shall furnish a double covering for the chest and abdomen and which can be easily put on and fastened in place and readily unfastened and removed.

15 This invention also aims to obviate the use of buttons or pins for securing the same in place and provides improved fastening means which can be easily and quickly secured and which will hold the shirt closely 20 and smoothly to the body of the wearer.

The present invention is an improvement over that shown in my prior Patent 877,416, issued January 21, 1908, and is designed to overcome certain defects therein, particularly 25 the wrinkling of the shirt occasioned by the tying together of the ends of the tapes which hold the inner flap of the under shirt in position when folded over across the front of the body.

30 With these and other objects in view it will be apparent from the following description that the invention consists of certain novel features of construction, one preferred embodiment of which is shown on 35 the accompanying drawing in which—

Figure 1 is a view of the shirt with both front flaps open; Fig. 2 is a view with the inner flap closed; and Fig. 3 is a view showing both flaps closed and securely fastened 40 in position.

The shirt as shown on the drawings consists of a body portion comprising a back 5, an inner front flap 6 and an outer front flap 7, these flaps being preferably made 45 integral with the back although it will be obvious that they may be made in separate pieces if found expedient or desirable. The sleeves 8 are of the usual shape and construction and may be secured to the body 50 in the ordinary manner. The inner flap 6 which is adapted to lie next to the chest and abdomen of the wearer is provided adjacent its free edge with a reinforcing tape 9. A free end 10 projects laterally from the re-

inforcing tape midway its ends; this projecting end being either a part of the tape 55 or a separate piece secured thereto. A companion tape 11 adapted to be tied to the projecting end 10 has one end secured to the outside of the body of the shirt substantially 60 beneath one of the arms. In order that the tape 10 may be brought into coöperative relation with the tape 11, I have provided a hole or opening 12 through the body of the shirt and the end of the tape 11, where it 65 is secured to the body, so that said tape serves to reinforce the hole and prevent its stretching or tearing out. When the shirt is put on the end 10 is first inserted through the hole 12 as shown in Fig. 2, then the 70 ends 10 and 11 are tied or otherwise secured together thus holding the inner flap in position by a single fastening means.

The outer flap 7 is adapted to fold over and against the outer face of the inner 75 flap thus affording a double thickness of material over the chest and abdomen. The free edge of the outer flap has secured thereto, preferably by stitching, a tape 13 which is secured throughout a central portion of 80 its length leaving both ends 14 free. A companion tape 15 is secured by stitching or otherwise to the side of the body of the shirt beneath the other arm leaving the two ends 16 of the tape free to be tied or 85 otherwise fastened to the free ends 14, whereby the outer flap is held in position as shown in Fig. 3.

It will be noted that in the present construction I employ but a single fastening 90 means for holding the inner flap in position, consisting of a single tape attached to the free edge of the inner flap midway its length, the tape being disposed so as to permit its free end to be passed through the 95 opening 12 in the body of the shirt and tied to the free end of the tape 11 secured to the body and serving to reinforce the opening 12. This arrangement enables the inner flap to be easily and quickly fastened without the employment of pins or buttons by simply passing the end 10 through the hole 12 and tying it to the end 11. It will also be noted that the tapes for securing the outer flap in position provide two free ends 100 spaced so as to come above and below the abdomen and above and below the inner flap fastening. This arrangement of the 105

fastening tapes prevents separation or gapping of the flaps and maintains the shirt closely to the body without undue pressure.

From the above it is believed that the construction and many of the attendant advantages of this invention will be apparent without further description and that the embodiment disclosed herein is capable of varied structural modifications within the scope of the invention.

I claim:

A garment having a back and inner and outer overlapping flaps forming the front, a tape secured to the free edge of the inner

flap, the other flap having an opening disposed adjacent the line of fold of the flap in transverse alinement with the point of attachment of the tape and adapted to receive the tape therethrough when the inner flap is closed, and a tape secured to the outer side of the outer flap adjacent said opening in position to permit tying of the two tapes, substantially as described. 15 20
